US00D836241S

(12) **United States Design Patent** (10) Patent No.: US D836,241 S
Packard et al. (45) Date of Patent: ** Dec. 18, 2018

- (54) **HEADLIGHT FACE PLATE BASE**

(71) Applicant: **DBMP, LLC**, Bountiful, UT (US)

(72) Inventors: **Jacob Dennis Packard**, Farmington, UT (US); **Jace Derrick Packard**, Farmington, UT (US)

(73) Assignee: **DBMP, LLC**, Bountiful, UT (US)

(**) Term: **15 Years**

(21) Appl. No.: **29/621,206**

(22) Filed: **Oct. 5, 2017**

Related U.S. Application Data

- (63) Continuation of application No. 29/580,858, filed on Oct. 13, 2016, now Pat. No. Des. 799,740, which is a continuation of application No. 29/516,473, filed on Feb. 3, 2015, now Pat. No. Des. 771,862.

CLAIM

The ornamental design for a headlight face plate base, as shown and described.

DESCRIPTION

FIG. 1 is a perspective view of a headlight face plate base showing our design;

FIG. 2 is a front elevational view thereof;

FIG. 2 is a front elevational view and

FIG. 4 is a top plan view thereof;

FIG. 5 is a bottom plan view thereof;

FIG. 6 is a left elevational view thereof; and

FIG. 7 is a right elevational view thereof.

Dash-dash broken lines showing environment

ings are included for illustrative purposes only and form no part of the claimed design. Dash-dot-dash broken lines shown in the drawings define the boundaries of the claim and form no part thereof.

1 Claim, 5 Drawing Sheets
